United States Patent Office

Des. 192,176

Patented Feb. 6, 1962

192,176

PLATE OR SIMILAR ARTICLE

Björn Wiinblad, Selb, Bavaria, Germany, assignor to Rosenthal-Porzellan Aktiengesellschaft, Bavaria, Germany, a corporation of Germany

Filed May 2, 1961, Ser. No. 65,008

Term of patent 14 years

(Cl. D44—15)

FIG. 1.

FIG. 2.

FIGURE 1 is a plan view of a plate or similar article of conventional configuration, showing my new design, it being understood that the ornamentation continues around the entire periphery in the pattern shown;

I claim:

The ornamental design for a plate or similar article, as shown and described.
